[57] CLAIM

The ornamental design for a gastrostomy tube, as shown.

DESCRIPTION

FIG. 1 is a perspective view of a gastrostomy tube, showing our new design;

FIG. 2 is a front elevational view thereof;

FIG. 3 is a fragmentary side elevational view thereof, the opposite side elevational view being identical thereto;

FIG. 4 is a rear elevational view thereof;

FIG. 5 is a perspective view of a second embodiment of the gastrostomy tube shown in FIG. 1;

FIG. 6 is a front elevational view thereof;

FIG. 7 is a fragmentary side elevational view thereof, the opposite side elevational view being identical thereto; and,

FIG. 8 is a rear elevational view thereof.

FIG. 1

FIG. 2

FIG. 3

FIG. 4

FIG. 5

FIG. 7

FIG. 8
